ABSTRACT OF THE DISCLOSURE

An apparatus for imparting an electrical pulse to a flowing stream of water having an inlet and outlet, a cathode within said housing in the path of said stream and an electric pulse generating means connected to said cathode.

An objective of this invention is to impart a series of electric pulses to a chamber in which a fluid is disposed. More specifically, this invention provides means for imparting said pulses to a moving stream of water.

Another objective of this invention is to provide an improved cathode assembly with sealing means for sealing the water chamber and having different means for carrying the pulse to the cathode within the chamber.

These and other objects of the invention will become more obvious to those skilled in the art by reference to the following detailed description when viewed in light of the accompanying drawings wherein like components thereof are indicated by like numerals throughout the figures and wherein:

FIG. 1 is a sectional elevational view of an apparatus in accordance with the invention, together with pulse generating circuitry.

FIG. 2 is a variation in the electrical circuitry of the device of FIG. 1; and

FIG. 3 illustrates a parallel "ganged" arrangement of devices in accordance with the invention.

In FIG. 1, a water treating apparatus, in accordance with the invention shown generally as 4, is composed of a cylindrical tank 6 having an inlet 8 at one end thereof and an outlet 10 the other end thereof.

An electrode conductor 24 is connected to the anode 13 through the ring 20. One end of tank 6 is enclosed by a cap 11. The other end of tank 6 is enclosed by a closure assembly 12. The assembly 12 supports an elongated anode 13 within and in spaced relationship to the tank 6. One end of the anode 13 is affixed to a non-conducting plastic disc 14. A second plastic disc 15 is secured to disc 14 by way of a screw 16. Disc 15 is apertured at 17 and the end of anode 13 is threadably bored at 18 to receive the screw 16. An annular ring 9, of copper or other conducting material, is secured about the outer periphery of disc 15. A smaller ring 20, of copper or other conducting material, is disposed on disc 15 inwardly of the ring 19. The ring 19 is also apertured to receive the screw 16.

The assembly 12 further includes a brass retainer sleeve 21 having an inwardly directed flange 22 adapted to abut the end of tank 6. The outer surface of sleeve 21 is threaded to receive threaded collar 23. The collar 23 is formed with an inwardly directed flange 24 which abuts ring 19.

Adjacent the flange 22, the interior surface of sleeve 21 is formed with a frusto-conical surface 24. An O-ring 25 can be disposed between the disc 14 and the conical surface 24 to aid in sealing tank 6, and a return current conductor 26 is connected to the wall of the tank 6 through ring 19.

The electrical circuitry for the embodiment of FIG. 1 is designated by a power main 32 controlled by a switch and a current limiting device feeding into a transformer 34. A pair of rectifying circuits 36 and 38 lead from the

2

secondary windings of the transformer 34. The circuit 36 leads through a rectifying diode 40 and a silicon controlled rectifier 42 to the electrode conductor 24 and returns through the return conductor 26. The circuit 38 includes a pilot light 44, a rectifier composed of rectifying diodes 46 and a regulator 48 made up of transistors T1 and T2 and a Zener diode 50. The above components made up by the described circuitry are known in the art and the particular circuitry is a matter of choice as is well known to the designer skilled in the art, so long as a direct current signal of controlled voltage level is provided.

A conductor 52 connects the voltage regulator 48 to a free-running multi-vibrator 54 which, through transistors T3 and T4, provides a square wave signal, the frequency and/or shape of which is controlled by mechanically interconnected variable resistors 56. The signal from the multi-vibrator is transmitted to an amplifier 58 where the conductive level is controlled by variable resistor 60. The output from the amplifier 58 transmitted to a pulse transformer which transmits a spike pulse through a diode 64 to the silicon controlled rectifier 42 for transmission to the electrode 16 through the conductor 24.

In operation, the pulse rate and intensity excitation is determined and set into the circuitry through the proper adjustment of the control for the multi-vibrator 54 and the conductive level adjustment for the amplifier 58. A fluid is circulated through the inlet 8 in the tank 6 and the electrode is energized so that electrostatic pulses of the desired rate and amplitude is imparted to the fluid between the anode 13 and the wall of tank 6.

Turning now to FIG. 2 of the drawings, a vacuum tube equivalent of the circuit of FIG. 1 is illustrated. In this figure, components corresponding to like components of the preceding figure are indicated by like numerals only of the next higher order. In this figure, the apparatus 104 is connected to an electrode conductor 124 and a return conductor 126 which are, in turn, connected to pulse rate and wave shape forming circuitry which circuitry consists in most aspects of a vacuum tube equivalent of the transistorized circuit shown in FIG. 1. In this figure, power mains 132 are connected to a transformer 134 through a switch and current limiting device. A first secondary coil in the transformer 134 is connected to a rectifying circuit 136 which, through a diode rectifier 140 is connected to the electrode conductor 124. A circuit 166, bypassing the transformer 134, is connected on one side, to the return conductor 126 and on the other side, to a free-running multi-vibrator 154. The free-running multi-vibrator 154 comprises a pair of triodes 168, the cathodes of which are connected to the circuit 166 and the plates of which are connected to the return side of the circuit 166 through a rectifying diode 146. Interconnected variable resistors 156 control the bias on the grid of the triodes 168 so that the frequencies of the square wave pulse emitted from the multi-vibrator 154 are regulated in a manner well known to those skilled in the art. The output from the multi-vibrator 154 is transmitted to a pentode amplifier 158 the conductive level thereof being controlled by a variable resistor 160. The output from the amplifier 158 is transmitted to the electrode and return conductors 124 and 126, respectively. The wave form of the output is altered between by the discharge device 142 to provide a spiked pulse signal when desired.

The vacuum tube circuitry, as shown in FIG. 2, operates in a manner similar to that of the transistorized circuitry of FIG. 1 for the same purposes. By control of the free-running multi-vibrator 154 and the conductive level of the amplifier 158, the pulse rate and the wave shape imparted to fluid in the tank 104 can be adjusted.

In FIG. 3, apparatus for utilizing the device of this invention in multiple or bank form is shown. In this figure,

a pair of tanks are connected in parallel through an inlet conduit 70 connected to the inlets 8A and 8B of the tanks shown and an outlet conduit 72 connects the outlets 10A and 10B of the tanks shown. The electrode conduits 24A and 24B and the return conduits 26A and 26B are connected to buses 74 and 76 as shown. A plurality of tanks can be arranged in this manner to impart a succession of pulses to traveling fluid.

What has been set forth above is intended as exemplary of teachings in accordance with the invention to enable those skilled in the art in the practice thereof. It should, therefore, be understood that, within the scope of the appended claims, the invention may be practiced other than as specifically described.

What is novel and therefore desired to be protected by Letters Patent of the United States is:

1. An apparatus for imparting an electrical pulse to a moving fluid comprising,
  - a cylindrical container having an inlet and an outlet, an elongated tubular element member extending into said container and defining an annular space therewith,
  - first means for circulating a fluid from said inlet through said annular space and departing through said outlet,
  - a plastic disc means affixed to one end of said electrode, second means engaging the periphery of said disc means and supporting said electrode member in spaced, insulated relation along the axis of said cylindrical container,
  - a source of low frequency, pulsating electrical energy connected to said electrical and said container for imparting a low frequency electrostatic pulse to a fluid in said container,

5

10

20

30

a first conducting ring electrically connected to said source and mounted on said disc, a second conducting ring on said disc electrically connected to ground potential, third means powered by a controlled source of direct current energy to vary the frequency and intensity of said pulse including in series,

a free-running multivibrator having a circuit means for adjusting the frequency thereof, an input adjustment means for varying the amplitude of the output of said free-running multivibrator, an output transistor amplifier connected to the input adjustment means, and an output pulse generator connected to the output of said transistor amplifier for providing said electrostatic pulse to the fluid in said container.

2. The apparatus in accordance with claim 1 wherein a plurality of containers are connected in parallel with said first-mentioned container.
